UNITED STATES PATENT OFFICE.

CHARLES W. GASTON, OF FRESNO, CALIFORNIA.

ELECTRIC THERAPEUTIC INSTRUMENT.

932,775.

Specification of Letters Patent. Patented Aug. 31, 1909.

Application filed June 5, 1909. Serial No. 500,242.

To all whom it may concern:

Be it known that I, CHARLES W. GASTON, citizen of the United States, residing at Fresno, in the county of Fresno and State of California, have invented new and useful Improvements in Electric Therapeutic Instruments, of which the following is a specification.

My invention pertains to electric therapeutic instruments such as are designed more particularly for use as suppositories; and it has for its object to provide a simple and inexpensive instrument of the kind stated, and one constructed with a view of contributing to the comfort and health of a patient, and adapted to be expeditiously and easily recharged with excitant when necessity demands.

The invention will be fully understood from the following description and claims when the same are read in connection with the drawings, accompanying and forming part of this specification, in which:

Figure 1 is a side elevation of my novel instrument as the same appears when ready for use. Fig. 2 is a view showing the tubular body of the instrument in section, and also showing the closure plug in elevation and as separated from the said tubular body. Fig. 3 is a transverse section taken through the tubular body of the instrument in the plane indicated by the line 3—3 of Fig. 2. Fig. 4 is a side elevation of a modification. Figs. 5 and 6 are enlarged detail sections of the modified construction, hereinafter specifically referred to.

Referring by letters to the said drawings, and more particularly to Figs. 1, 2 and 3, thereof: A is the tubular body of my novel instrument, which is formed of glass or any other rigid non-conductor of electricity. The said tubular body A is open at its ends, Fig. 2, and is provided in its outer side with a plurality of spaced, longitudinal grooves a, which extend throughout its length, as will be observed by comparison of Figs. 1 and 3. B is a plug, flanged as indicated by b, and designed to be removably secured in one end of the body A by frictional contact or by a screw-thread (not shown) or other conventional means, and C is a plug designed to be similarly secured in the opposite end of body A. The plugs B and C are preferably, though not necessarily, of the same material as the body A, and the plug C is tapered, for obvious reasons, while the

perimeter of the flange b on plug B is preferably milled, as illustrated. The longitudinal grooves a in the outer side of the body A are designed to receive the wires D and E, which are preferably of zinc and copper, respectively. At the ends of the said grooves a the wires are carried inwardly through notches e, formed in the ends of the body A, and are then bent inwardly toward the transverse center of the body, and are pressed close against the inside thereof. It will thus be seen that with the plugs B and C positioned in the ends of the body the wires D and E will be securely retained in proper position with respect to the body and against casual movement, and yet when desired any one of the wires may be expeditiously and easily removed and as readily replaced with a new wire. It will also be observed by reference to Fig. 2 that the arrangement of the terminals of the wires close against the inside of the body A leaves room in the said body to receive an adequate quantity of raw cotton or other absorbent material, (not shown) designed to be saturated with a little common vinegar or any other suitable excitant. When the instrument is put in use in the ordinary well known manner, the electrical circuits between the wires D and E will be completed, and a mild galvanic action will be created and maintained, with the result that the patient will be benefited in a manner common to electric therapeutic instruments of the kind set forth.

In the modified construction shown in Figs. 4, 5 and 6, the grooves a' in the outer side of the body A' are spiral, instead of straight, and the wires D' and E' are also spiral, and hence are adapted to present an increased length of surface to the body of the patient. With these exceptions, however, the modified embodiment is similar to that shown in Figs. 1, 2 and 3, and is used in the same manner. It will also be understood that in the modified construction any one of the wires D' or E' may be readily removed when necessary and replaced with a new wire.

In addition to the practical advantages hereinbefore ascribed to my novel instrument, it will be noticed that the same is compact and light, as well as simple and inexpensive, and is adapted to be easily maintained in proper working order.

In the embodiment shown in Fig. 4, the

105

head b' is of the peculiar shape illustrated and hence said embodiment is adapted for use in the treatment of womb troubles.

Having described my invention, what I claim and desire to secure by Letters-Patent, is:

1. An electric therapeutic instrument, comprising a tubular body open at its ends and adapted to receive and hold material
- 10 suitable to its purpose and having grooves in its outer side and notches in its ends in communication with said grooves, wires of opposite metals arranged in the said grooves of the body and extending through notches
- 15 in the ends of the body, and having end portions arranged in the body and snug against the inner side thereof, and plugs removably

arranged in the ends of the body, substantially as and for the purpose set forth.

2. An electric therapeutic instrument, 20 comprising a tubular body open at its ends and exteriorly grooved, wires of opposite metals arranged alternately in the grooves of the body and having end portions extending within the body, and end closure plugs 25 removably arranged in the ends of the body and retaining the wires in position.

In testimony whereof I have hereunto set my hand in presence of two subscribing witnesses.

CHARLES W. GASTON.
